UNITED STATES PATENT OFFICE.

WESLEY F. HALL, OF MATAWAN, NEW JERSEY, ASSIGNOR TO A. P. MUNNING & CO.
OF NEW YORK, OF NEW YORK, N. Y., A CORPORATION OF NEW JERSEY.

BUFF WHEEL.

Application filed September 26, 1921. Serial No. 503,410.

The invention relates particularly to polishing or buffing wheels built up from pieces of flexible fabric such as muslin, canvas, flannel, felt, or similar material used for this purpose, the pieces ordinarily being cut from large sheets into a form suitable for assemblage to make up the complete wheel.

One object of the invention is to construct a buff wheel into which the material of a large sheet may be substantially completely incorporated, without the production of waste fragments left after the sheet has been cut up into pieces.

Another object is to provide a wheel which, when run in opposite directions for "cutting" and "coloring" operations, will present a working surface which is relatively compact in form for "cutting" and soft or loose for "coloring".

Other objects are to secure a wheel which may be accurately balanced, and in cases where woven material is used, to minimize fraying or pulling out of the threads in use.

Further objects and advantages of the invention will be in part obvious and in part specifically pointed out in the description hereinafter contained, which, taken in connection with the accompanying drawings, discloses a preferred embodiment of the invention; such invention, however, is to be considered merely as illustrative of its principle. In the drawings:

Fig. 1 is a view of a sheet of material indicating lines along which the sheet may be cut to obtain pieces of such form that they may be assembled to make up a buff wheel constructed in accordance with the invention.

Fig. 2 is a view similar to Fig. 1, but indicating a manner in which the sheet may be cut to obtain pieces having their working edges inclined to both the warp and weft of a woven sheet, whereby the working face of the wheel may consist of the ends of the threads instead of their sides.

Fig. 3 is a perspective view of a buff wheel constructed in accordance with the invention and made up of pieces similar to those indicated in Fig. 2.

Figs. 4 and 5 are respectively a plan view and an edge view of a portion of the wheel shown in Fig. 2.

The fabrics from which buffing wheels of the above character are made, are usually

obtained in the form of long rolls or sheets from which the pieces are cut into proper form for assembling to make up a circular buff wheel. If the structure of the wheel and the relation between the pieces making up the same are such that the working edges of the pieces must be cut circular or arc shaped, a large number of waste pieces of material will be left over after the pieces necessary to make up a wheel have been cut from the sheet, owing to the fact that the circular or arcuate sides of the pieces are necessarily spaced from each other in the sheet, at all points except a common point of tangency between adjacent circles. Thus the wastage of material, which easily may amount to 15% or 20% of the total area of the sheet, becomes a substantial factor in the cost of the wheel.

According to the present invention, the wheel is made up of pieces of such form that substantially the entire area of a rectangular sheet of material may be divided up to obtain the pieces without waste; nevertheless the structure of the wheel and the method of assembling the pieces to make up the same, are such that the completed wheel is substantially uniform in thickness and so approximately circular in shape in the first instance, that no substantial wastage of material results from the operation of truing up its working face. The above and other features and advantages of the wheel will be more apparent from more detailed description hereinafter contained.

In my co-pending application Serial No. 503,411 filed September 26, 1921, entitled Method of cutting material for buffing wheels, I have described a method of severing a rectangular sheet of material without substantial wastage into pieces adapted to be assembled into a buff wheel constructed in accordance with this invention, reference hereby being made to said co-pending application for a more complete description of such method.

Briefly described, a rectangular sheet 1 of suitable material may be severed along a series of lines 2 parallel to one edge 3 of the sheet, and also along a further series of parallel lines at an angle to lines 2, thus forming parallelograms between lines 2 and 4 having opposite sides 2^a and 4^a respectively. The sheet 1 may also be severed along a further series of parallel lines 5 which divide

up the parallelograms previously mentioned into polygons having diverging sides 2^a and 5^a respectively. Thus according to the specific showing of Fig. 1, the rectangular sheet 1 is cut up into a plurality of equal right angled triangles which utilize the whole area of the sheet.

If the sheet 1 be of woven material, the sides 4^a of the triangles which are to make up the working face of the wheel, will be parallel to either the warp or weft, and thus the threads of the pieces which run along the working edge of the wheel might easily be frayed out or unravel, rendering the working face uneven, instead of wearing out usefully and evenly. In Fig. 2 I have illustrated a method of cutting up a sheet to obtain pieces with working edges oblique to both the warp and weft, and still substantially the entire area of the sheet is usefully employed. In Fig. 2 the warp threads are indicated by numeral 10, and the weft threads by numeral 11. The sheet may be severed along a series of parallel lines corresponding to lines 2 of Fig. 1, but the lines 12 of Fig. 2 which define the working edges of the pieces, instead of extending at right angles to the lines 2, as is the case with lines 4 of Fig. 1, run obliquely across the sheet, and thus the working edges 12^a of the pieces are made up of the ends of both the warp and weft threads. The sheet may be severed along further lines 5 similar to those described in connection with Fig. 1, the result being that the sheet in the particular form of the invention indicated in Fig. 2, is cut up into isosceles triangles with their bases inclined to both the warp and weft. According to Fig. 2 the material of the lower left hand and upper right hand corners of the sheet is cut into pieces smaller than those which occupy the major portion of the area of the sheet, but for the most part the smaller pieces are regular in shape and adapted for use in smaller size buff wheels; thus no substantial wastage of material is necessary to obtain working edges of the above character.

The preferred method of assembling pieces of the above character will be described in connection with Figs. 3 to 5.

I prefer to employ pieces the working edges 12^a or 4^a of which are substantially tangent to a circle described about the intersection point of the diverging sides 2^a and 5^a as a centre. The pieces then may be assembled with their sides 2^a and 5^a extending substantially radially from the centre of the wheel to be formed, and their remaining sides or bases 12^a substantially tangent to a circle described about the centre of the wheel to be formed, the pieces being angularly spaced to make up the complete circle of the wheel, and bound together in any suitable manner, as by rows of stitching 6

(Figs. 3 and 4), and a circular hole 7 formed at the centre to enable the wheel to be slipped over a spindle.

I prefer to assemble the pieces with the centre point of the wheel located somewhat beyond the intersection point of their diverging sides 2^a and 5^a, in such manner that the apices of the triangles are located adjacent the walls of the hole 7. This will result in a saving of material, since if a 16" wheel is to be made up, for example, the pieces need be cut to a length only of about 7" instead of 8", and yet sufficient material will be provided at the centre of the wheel for the hole 7.

As appears more clearly in Fig. 4, the working surface of the wheel will be made up in the first instance of the projecting corners 8 of the pieces, and the wheel will not have a truly circular periphery until these corners are cut down to the circle 9 (Fig. 4) to which the working edges 12^a are tangent. However, it ordinarily is impracticable to cut and assemble pieces of any shape so accurately as to form a wheel which is truly circular in the first instance, and therefore the wheels are usually trued up after being completed by cutting off the necessary amount of material from the working face to form an exact circle. I prefer to form the pieces with their working edges 12^a or 4^a relatively short as compared to their remaining sides, whereby only a relatively small fraction of each piece lies exterior to the circle 9, thus reducing the amount of material cut off in the truing up operation. In fact, the removal of material or reduction in diameter due to the truing up operation need not be greater with pieces of the character previously described, than would be the case with other types of wheels, and thus no increase in loss of material is involved.

I prefer to make up the wheel by superposing successive pieces one against the other as indicated in Figs. 3 to 5, with each successive piece at a slight angle to the one respectively preceding, whereby each piece overlaps the adjacent one slightly, the pieces being successively superposed until the complete circle of the wheel is formed by overlapping the last piece with the first. Thus a wheel unit is formed of a thickness commensurate with one which would be obtained by assembling a number of flat layers or plies, the thickness of the unit depending upon the angularity between the several pieces. The utility of this method of assemblage obviously is not limited to the particular form of pieces previously described.

It will be noted that the working surface of a wheel built up in the above manner is made up of edges of the pieces which are inclined to the plane of the wheel, and thus each edge has a draw cutting action which

- is advantageous in use, and tends to make the wheel cut and wear away evenly. Furthermore, the entire periphery of the wheel is substantially symmetrical as regards both 5 the warp and weft, and if the pieces be cut in the first instance with their working edges oblique to the warp and weft, the symmetrical disposition of such pieces with respect to the periphery of the wheel will bring about 10 the result that the whole cutting surface is made up of the ends of the threads, without the disadvantage of threads running along the cutting surface which are liable to fray out. 15 Also in many applications of buff wheels it is desirable that for preliminary operations termed "cutting down", the wheel shall have a hard or compact surface, while for "coloring" or finish polishing operations 20 a softer and looser wheel periphery is desirable. Figs. 3 and 5 show a buff wheel made up of two sections or units 13 and 14 each of the structure previously described, but with the working edges of the pieces oppositely inclined to the plane of the wheel, resulting in a wheel face of a herring bone appearance. It will be noted that the side edges of the pieces in each unit are exposed 25 at the side of the wheel, and thus when the latter rotates at a high velocity in the direction of the arrow shown in Fig. 3, the effect of the air resistance upon the pieces is to flatten down their side edges, rendering the surface of the wheel particularly advantageous for "cutting down" operations. 30 On the other hand, if the wheel be run in the opposite direction, the action of the air upon the inclined cutting edges and exposed side edges of the pieces tends to spread the same, and thus bring about a working surface which is soft and loose, and therefore particularly advantageous for "coloring". 35
- While certain embodiments of the invention have been described, it is obvious that many changes may be made therein without departing from the spirit of the invention 40 as defined in the following claim.
- I claim:
- A buff wheel comprising two separate series of fabric pieces angularly stepped and 45 lapped to make up complete circles, the working edges of the pieces in the said series being oppositely inclined to the plane of the wheel.
- In testimony that I claim the foregoing, 50 I have hereunto set my hand this 8th day of September, 1921.
- WESLEY F. HALL.
